UNITED STATES PATENT OFFICE.

EDWARD L. GARFIELD, OF TUCKAHOE, NEW YORK.

FAN OR BLOWER.

1,381,819.

Specification of Letters Patent. Patented June 14, 1921.

Application filed March 22, 1920. Serial No. 367,945.

To all whom it may concern:

Be it known that I, EDWARD L. GARFIELD, a citizen of the United States, and a resident of Tuckahoe, in the county of Westchester 5 and State of New York, have invented a new and Improved Fan or Blower, of which the following is a description.

My invention relates to a fan or blower and more particularly is designed for embodiment in a ventilating fan.

The general object of my invention is to provide a fan or blower improved in various particulars with a view to promote facility in the making and assembling of the structural elements entering into the fan and its frame; as well as to promote convenience in the installation of the fan in a ventilating system for example, and to provide a fan having durability and made up of a few and 20 simple parts.

The invention resides in the novel construction of the fan and the bracing means for the blades thereof as well as in the novel arrangement of the fan casing and its frame, 25 looking to the attainment of strength in the frame and the proper housing and guarding of the blades and the fan hub; a further important object being to provide a frame construction of a character to insure that the 30 adjustable bearings for the fan shaft will be maintained in alignment and distorting strains set up in the fan when in operation be resisted.

Reference is to be had to the accompanying drawings forming a part of this specification, it being understood that the drawings are merely illustrative of one example of the invention.

Figure 1 is a front elevation of a fan embodying my invention;

Fig. 2 is a transverse section taken through the fan as indicated by the line 2—2, Fig. 1;

Fig. 3 is a fragmentary face view showing a portion of the fan with the fan hub and 45 one of the blades, and the hub disk to which the blades are secured and bracing means for the blade;

Fig. 4 is an enlarged cross section through one of the blades as indicated by the line 50 4—4, Fig. 3.

In carrying out my invention in accordance with the illustrated example the hub 10 of the fan is mounted on the fan shaft 12 as by a set screw 11. Said shaft turns in 55 any approved ball bearings, the casings of which are indicated by the numeral 13. The

numeral 14 indicates bearing mounts forming part of spiders 15 at each side of the fan and supporting the casings 13 through the medium of adjusting and centering screws 16. 60

The bearing mount 14 of each spider presents arms 14^a deflected laterally inward and forming part of the same conical surface, said arms being suitably secured as by bolts 15^a or the like to the spider arms 15. The 65 arms of the respective spiders 15 are outwardly divergent relatively to each other while the spiders are deflected bodily toward each other and toward the medial plane of the fan to thus give the frame a truss form. 70 The outer ends of the spider arms are fastened to a frame 17 here shown as a rectangular frame, made up of angle bars, the connecting means being corner pieces 18 provided on said frame and serving to stiffen 75 the same, to which corner pieces the outer ends of the arms are secured by bolts or rivets 15^b. The corner pieces 18 are here indicated as secured by bolts 19 to the angle bars of the frame 17 and said bolts also secure a web 20 provided within said frame in a plane approximately medial of the fan structure, said web carrying a cylindrical casing 21 within which the fan revolves. The casing 21 is made rigid by any suitable 80 means with the web 20, there being shown a ring 22 of angle iron, the flanges of which are respectively fastened to said web and casing. The frame including the spiders 15 with the bearing mounts 14 as described 85 serves to rigidly sustain the bearing casings 13 in alignment and the result is attained by a construction involving few parts of extreme simplicity. In order to produce a fan of 90 light construction and having adequate strength and durability in accordance with my invention, said fan is made up as follows: The blades 23 are secured at their inner ends by bolts 25 or the like to a disk open to accommodate the shaft 12, said disk being 95 here shown as separate and of sheet metal secured by bolts 26 to the hub flange. The disk 24 it will be observed, has the relation to the hub 10 of a flange thereon for the securing 100 of the blades. 105

Each blade 23 is strengthened by a brace 27 at the inner end of the blade and extending to any desired distance toward the outer end of the blade. It will be observed that the brace 27 is at the back of the blade 23 110 between the same and the hub disk 24. For securing the blade and the brace said blade

along a side edge 23^a is disposed at an angle to the general plane of the blade and in a plane parallel with the plane of the hub disk 24. Similarly, the brace 27 at that side edge 5 27^a adjacent to the edge 23^a of the blade is disposed at an angle to the general plane of the brace, parallel with the edge 23^a and disk 24 and lying flat against the latter. Bolts 25 thereby secure both the inner end 10 of a blade edge 23^a and an edge 27^a of a brace. In addition said edges 23^a, 27^a, are secured by additional means such as rivets 29. The opposite side edge of the brace 27 is rigidly fastened also to the blade as by 15 rivets 28.

It will be observed from Fig. 4 that the flanged or bent edge portions 27^a of brace 27 has a width greater than that of the similar edge or flanged portion 23^a of blade 23, and the juncture of the flange 27^a and brace 27 is on a line laterally beyond the juncture of the flange 23^a with the blade 23, so that the body of the brace 27 is in a plane at an angle to that of the body of the blade 23, thereby producing a convergent intervening space 30. The arrangement is such that the brace of itself and without the employment of adventitious spacing means, serves to give the proper spaced relation 20 and relative angularity of the blade and its brace. Said brace flange, it will be seen, is directly applied to the hub disk and flatwise against it with the blade flange imposed flatwise directly on the brace flange, the result 25 being an exceedingly strong construction, yet involving the minimum simplicity and making for the facility with which the parts may be assembled.

I would state in conclusion that while the 40 illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim:

1. A fan including blades, a separate hub 50 having a blade carrying portion and braces for said blades, each blade having an edge portion thereof at an angle to the body of the blade, the brace of said blade having an edge portion at an angle to the body of the brace, said edge portions being in planes parallel with the said blade-carrying portion of the hub and being secured to the latter, the body of the blade and the body of the brace lying in planes at an angle to each other.
- 60 2. A fan including blades, a separate hub having a blade-carrying portion, and braces for said blades, each blade having an edge

portion thereof at an angle to the body of the blade, and the brace of said blade having an edge portion at an angle to the body of the brace, said edge portions being in planes parallel with the blade-carrying portion of the hub and being secured to the latter, the brace lying directly against said blade-carrying portion between the same and the blade 70 and the whole being secured together, the angular edge portion of the brace having a greater width than the angular edge portion of the blade to extend beyond the latter so that the body of the brace is at an angle to 75 the body of the blade.

3. A fan or blower including blades, a hub rigid therewith, a shaft on which the hub is secured, a fixed casing about said blades, a frame outside of said casing, a web 80 in the plane of the fan and secured respectively to said casing and to said frame, spiders at the sides of the casing, the arms of the respective spiders being outwardly divergent, means securing the spiders rigid 85 with the frame and web, bearing mounts carried by said spiders, and bearings for said shaft within said bearing mounts.

4. A fan or blower including a frame, a fan casing within said frame, means connecting the fan casing with the frame, spider arms divergent toward their outer ends, means rigidly connecting the outer ends of the spiders with the frame and the first-mentioned means, alined bearing mounts rigid 95 with the respective spiders, bearings in said mounts, a shaft turning in said bearings, fan blades within said casing and means mounting said blades and arranged to turn with said shaft.

5. In a fan, a frame, spiders at opposite sides of the frame, alined bearing supports in said spiders, a shaft turning in said bearings, fan blades, means mounting said fan blades to turn with the shaft, a casing 105 within said frame outside of said blades, a web disposed in the plane of the fan within said frame, said web being secured at its inner edge to said casing between the ends of said casing and secured at its outer edge to 110 said frame, said spiders at their outer ends being secured to said web.

6. In a fan, a rectangular frame formed of angle bars, corner pieces secured to said frame within the same, spiders at opposite 115 sides of the frame and secured to said corner pieces, bearings supported in said spiders, a shaft turning in said bearings, fan blades, means mounting said blades to turn with said shaft, a casing for said fan blades 120 within said frame, and means securing said casing to said frame, said means being secured to said spiders and corner pieces.

EDWARD L. GARFIELD.
